TRACTOR TRACK SHOE

John L. Deffenbaugh, Peoria, and Fred E. Simpson,
Washington, Ill., assignors to Caterpillar Tractor Co.,
Peoria, Ill., a corporation of California

Filed Sept. 2, 1964, Ser. No. 81,569

Term of patent 14 years

(Cl. D14—6)

FIG. 1.

FIG. 2.

FIG. 1 is a perspective view showing the ground engaging surface of the tractor track shoe embodying our new design;

FIG. 2 is a perspective view showing the side of the track shoe opposite to that shown in FIG. 1;

FIG. 3 is a front elevational view of the same track shoe;

FIG. 4 is a rear elevational view of the same; and

FIG. 5 is an end elevational view of one of two identical ends of the same.

We claim:

The ornamental design for a tractor track shoe, substantially as shown.
